UNITED STATES PATENT OFFICE.

LEWIS A. FRITSCH, OF FORT THOMAS, KENTUCKY, ASSIGNOR TO OHIO TRUSS COMPANY,
OF CINCINNATI, OHIO.

HEAD-BAND.

1,258,617.

Specification of Letters Patent.

Patented Mar. 5, 1918.

Application filed July 10, 1917. Serial No. 179,773.

To all whom it may concern:

Be it known that I, LEWIS A. FRITSCH, residing at Fort Thomas, Campbell county, State of Kentucky, have invented a certain new and useful Head-Band, of which the following is a clear, full, and exact description, attention being called to the drawing which accompanies this application and forms a part thereof.

10 In playing out-door games like tennis for instance vision is frequently interfered with by the hair which becomes disarranged by the wind and hangs into the eyes, also by perspiration which is apt to run into the eyes.

15 To overcome these difficulties I have provided a band, adapted to be worn around the head above the eyes and made of elastic material so as to readily fit and to remain in place.

20 It is of suitable width so as to engage the hair to hold the same up and out of the face.

25 The material is also absorbent so as to take up perspiration and to prevent the same from running down over the face and into the eyes.

The accompanying drawing shows the band at A and the manner of its use.

30 It serves also to support a vizor B of suit-

able material like leather for instance which is connected to the lower edge of the band and serves as a shield to protect the eyes against the sun.

The band is preferable to a cap inasmuch as it does not cover the top of the head and leaves the same free to the access of air.

The vizor, which is of leather or other pliant material, has its concaved edge portion overlapping and stitched to the lower edge portion of the band, as illustrated. It will be noted that when the band is applied to the head, the tension thereof will pull the concaved edge of the vizor snugly adjacent to the head to conform to the curvature thereof, thereby causing the vizor to assume its proper sloping position to shade the eyes. The vizor and band both being flexible can be folded up, when not in use.

Having described my invention I claim as new:

An article of headwear consisting solely of an elastic band, and a pliant vizor having a concaved edge attached to the lower edge of the band to hold the vizor in shape when drawn against the head by said band.

In testimony whereof I hereunto affix my signature.

LEWIS A. FRITSCH.
